UNITED STATES PATENT OFFICE.

VINCENZO TESTA, OF ST. CATHERINES, ONTARIO, CANADA.

MECHANICAL TOY AEROPLANE.

1,373,368.

Specification of Letters Patent. Patented Mar. 29, 1921.

Application filed August 27, 1920. Serial No. 406,378.

To all whom it may concern:

Be it known that I, VINCENZO TESTA, subject of the King of Italy, residing at St. Catherines, in the Province of Ontario and 5 Dominion of Canada, have invented new and useful Improvements in Mechanical Toy Aeroplanes, of which the following is a specification.

This invention relates to toys, particularly to mechanical toys, and has for its object the provision of a mechanical toy aeroplane adapted to be suspended from a suitable support and equipped with a spring motor driven propeller whereby the toy 15 will be caused to travel in a circular path.

An important object is the provision of a device of this character having a portion of the body formed as a cover which may be removed to permit access to the interior 20 mechanism for the purpose of making repairs or adjustments.

Another object is the provision of a device of this character in which the planes are pivotally mounted upon a cover member 25 so that they may be swung to lie along the body so that the device may be easily packed as it will occupy but relatively small space and not require as large a shipping box as if the wings were rigid in their 30 transverse position.

An additional object is the provision of a device of this character which will be simple and inexpensive in manufacture, highly efficient in use, durable and amusing, 35 and a general improvement in the art.

With the above and other objects and advantages in view, the invention consists in the details of construction to be hereinafter more fully described and claimed and illustrated in the accompanying drawings in 40 which—

Figure 1 is a plan view of the device,

Fig. 2 is a side elevation,

Fig. 3 is a longitudinal sectional view,

45 Fig. 4 is a cross sectional view taken in advance of the wings or planes,

Fig. 5 is a perspective view of the cover member, and

Fig. 6 is a plan view of the fuselage with 50 the cover and planes removed.

Referring more particularly to the drawings, the numeral 10 designates the body or fuselage of the device which is of the shape commonly used in aeroplane construction 55 and which is formed of any suitable light weight material, preferably tin. Depend-

ing from the underside of the body is an inverted U-shaped yoke 11 supported by inclined braces 12 and carrying wheels 13 which represent the landing gear of the 60 aeroplane. At its rear end the body 10 is provided with a transverse elevator plane 14 and a vertical rudder 15.

At its central portion the body 10 has its top provided with an opening 16 at the 65 sides of which are formed laterally extending lugs or ears 17. This opening is adapted to be closed by a removable cover 18 of a size and shape to cover the opening and still have the effect of forming a continuation of the body itself. At its side edges this cover carries ears or lugs 19 registering with the lugs 17 and detachably connected therewith by suitable bolts 20.

Located within the body is a spring motor 75 21 of any ordinary or preferred type and which includes a winding post 22 upon which a suitable key may be engaged for placing the spring motor under tension.

The motor of course includes the usual 80 train of gears indicated at 23, which operate to drive the ultimate shaft 24 which projects beyond the front end of the body and carries a propeller 25.

The numerals 26 and 27 designate the 85 planes which are formed of suitable material, which may be tin, and which are spaced apart by vertical struts 28. The planes are mounted upon the body 10 by means of a suitable bolt or rivet 29 which passes 90 through the center of the lower plane 27 and through the cover 18. By this connection it will be seen that the planes may be rotated so as to lie along the body so that the device may be packed readily for shipment or storage without necessitating the use of an excessively large box or the like. The lower plane 27 is formed with an ear or lug 30 through which passes a screw 31 screwed into the body for holding the planes 100 in position transversely of the body.

The numeral 32 designates a flexible member which may be a looped strap, wire, or the like, which passes centrally through the upper plane 26 and to which any suitable 105 suspending cord or the like may be attached by means of which the device may be suspended from the ceiling, a chandelier, or the like.

In the operation of the device it will be 110 seen that after the spring of the motor is placed under tension and the motor allowed

to operate the rotation of the propeller 25 will cause the device to travel in a circular path, giving the appearance of an aeroplane in flight.

5 From the foregoing description and a study of the drawings it will be apparent that I have thus provided a simply constructed and consequently inexpensive toy aeroplane which may be easily operated, 10 which will be very amusing and entertaining, and which will be durable and efficient in every way.

While I have shown and described the preferred embodiment of my invention, it is 15 of course to be understood that I reserve the right to make such changes in the form, construction, and arrangement of parts as will not depart from the spirit of the invention or the scope of the subjoined claims.

20 Having thus described my invention, I claim:

1. A device of the character described comprising a body provided in its top with an opening, a cover detachably secured upon 25 the body for closing said opening, and a pair of spaced planes rotatably carried by

said cover whereby to dispose them selectively in transverse relation to the body or to lie longitudinally therealong.

2. A device of the character described 30 comprising a body provided in its top with an opening, a cover detachably secured upon the body for closing said opening, a pair of spaced planes rotatably carried by said cover whereby to dispose them selectively 35 in transverse relation to the body or to lie longitudinally therealong, and means for holding said wings rigid in transverse relation to the body.

3. A device of the character described 40 comprising a body, a spring motor therein, a shaft extending from the forward end of the body and driven by said motor, a propeller on said shaft, a pair of planes pivotally mounted upon the top of the body and 45 adapted to be disposed longitudinally thereof or transversely thereof, and means for holding said planes in such transverse position.

In testimony whereof I affix my signature. 50

VINCENZO TESTA.
